(57) CLAIM

The ornamental design for a bottle, as shown and described.

DESCRIPTION

FIG. 1 is a front view of a first embodiment of a bottle showing our new design.

FIG. 2 is a side view of the bottle of FIG. 1.

FIG. 3 is a bottom view of the bottle of FIG. 1.

FIG. 4 is a rear view of the bottle of FIG. 1.

FIG. 5 is an angled bottom view of the bottle of FIG. 1.

FIG. 6 is a rear view of the bottle of FIG. 1.

FIG. 7 is another angled bottom view of the bottle of FIG. 1, shown without the broken line free throw circle surface ornamentation.

FIG. 8 is a front view of a second embodiment of a bottle showing our new design.

FIG. 9 is a side view of the bottle of FIG. 8.

FIG. 10 is a bottom view of the bottle of FIG. 8.

FIG. 11 is a rear view of the bottle of FIG. 8.

FIG. 12 is an angled bottom view of the bottle of FIG. 8.

FIG. 13 is a rear view of the bottle of FIG. 8.

FIG. 14 is another angled bottom view of the bottle of FIG. 8, shown without the broken line free throw circle surface ornamentation.

The broken lines illustrating “free throw circles” represent surface ornamentation and form part of the claimed design. The broken lines illustrating a “curved portion of the pedestal” supporting the bottle form no part of the claimed design. The dotted pattern surface-shading in the second embodiment represents surface texture and does not form part of the claimed design.
